UNITED STATES PATENT OFFICE.

WALTER E. McGRAW, OF EVERETT, MASSACHUSETTS.

DESIGN FOR A CLOCK-CASE.

No. 37,587.

Specification for Design.

Patented Oct. 24, 1905.

Application filed August 11, 1905. Serial No. 273,833. Term of patent 14 years.

To all whom it may concern:

Be it known that I, WALTER EDWARD McGRAW, a citizen of the United States, residing in Everett, in the county of Middlesex and Commonwealth of Massachusetts, have invented a certain new, original, and ornamental Design for a Clock-Case, of which the following, together with the accompanying drawing, forming a part thereof, is a specification.

The illustration shows a view in elevation of my design for a clock-case.

I claim—

The ornamental design for a clock-case as shown.

WALTER E. McGRAW.
